E. HAVILAND.

DISH.

No. 19,651.

Patented Feb. 18, 1890.

UNITED STATES PATENT OFFICE.

CHARLES EDWARD HAVILAND, OF LIMOGES, FRANCE.

DESIGN FOR A DISH.

SPECIFICATION forming part of Design No. 19,651, dated February 18, 1890.

Application filed December 26, 1889. Serial No. 335,032. Term of patent 14 years.

To all whom it may concern:

Be it known that I, CHARLES EDWARD HAVILAND, a citizen of the United States, residing at Limoges, in the Republic of France, have invented and produced a certain new and original Design for Dishes of a Table-Service, fully described and represented in the following specification and the accompanying drawing, forming a part of the same.

The distinguishing characteristics of the design are the shape of the dish and its edge ornamentation, fully represented in the accompanying illustration, in which is illustrated by a plan view a platter embodying the present design. The dish therein shown is of substantially rectangular form, having rounded corners 11 and 22. The edge of the platter flares upwardly and outwardly from the body 3 of the platter, and at its ends is provided with inward bends 4. Diametrically-opposite corners are fac-similes; but those upon each end of the platter are different from each other. A description of one side of the dish will therefore suffice. The corner edge 1 is formed with inward bends 5 6, forming an outward curve 7. From the inward bend 5 to the inward bend 4 at the

end of the platter the edge of the platter is fluted or wrinkled, as shown, and from the bend 6 to an inward bend 8 in the side of the dish the edge is similarly fluted or wrinkled. From thence to an outward curve 9 the edge is somewhat more irregularly fluted or wrinkled, as shown. The curve 9 terminates at each end in a scroll 10, extending inward toward the body of the platter. The corner edge 2 is irregularly fluted or wrinkled from the curve 9 to the inward bend 4 in the opposite end of the dish. In each of the curves 12 is a scroll 11, curved to approximately the outlines of the corners.

What I claim is—

1. The design for the shape of a dish, substantially as herein shown and described.
2. In a design for a dish herein shown and described, the surface ornamentation of the same.

In testimony whereof I have hereunto set my hand in the presence of two subscribing witnesses.

CHARLES EDWARD HAVILAND.

Witnesses:

ALBERT HAVILAND,
GASTON LONGEVIALE.
